(57) CLAIM

The ornamental design for a pet licking pad, as shown and described.

DESCRIPTION

FIG. 1 is a top, front, left perspective view of a pet licking pad, showing my new design;

FIG. 2 is a bottom, front, left perspective view thereof;

FIG. 3 is a top, front, right perspective view thereof;

FIG. 4 is a front elevational view, the rear elevational view being a mirror image thereof;

FIG. 5 is a left side elevation view, the right side being a mirror image thereof;

FIG. 6 is a top plan view thereof;

FIG. 7 is a bottom plan view thereof;

FIG. 8 is a top, front, left perspective view of the pet licking pad of FIG. 1, shown exploded for clarity of disclosure thereof;

FIG. 9 is a bottom, front, left perspective view of the pet licking pad of FIG. 1, shown exploded for clarity of disclosure thereof;

FIG. 10 is a partial enlarged bottom, front, left view of the detail identified in FIG. 2 thereof; and,

FIG. 11 is a partial enlarged bottom plan view of the detail identified in FIG. 7.

In the drawings, the equal-length broken lines depict portions of the pet licking pad that form no part of the claimed design. The dash-dot-dash broken lines are for annotating enlarged views. All broken lines form no part of the claim.

1 Claim, 11 Drawing Sheets
